UNITED STATES PATENT OFFICE.

JAKOB SPTCHALSKI, OF SOUTH BETHLEHEM, PENNSYLVANIA.

PARACHUTE.

1,120,755.

Specification of Letters Patent. Patented Dec. 15, 1914.

Application filed August 28, 1914. Serial No. 359,094.

To all whom it may concern:

Be it known that I, JAKOB SPTCHALSKI, a subject of the Czar of Russia, residing at South Bethlehem, in the county of Northampton and State of Pennsylvania, have invented certain new and useful Improvements in Parachutes, of which the following is a specification.

This invention relates to certain new and useful improvements in parachutes.

A primary object of this invention is to provide a foldable device adapted to carry a person in descending from high altitudes such as from balloons, aeroplanes, and high mountains.

A further object is to provide an umbrella form of device automatically foldable and having a platform or support for a passenger and whereby a person may open the device from the platform and gently and slowly descend from high altitudes without sustaining any personal injuries.

With these general objects in view and others that will appear as the nature of the invention is better understood, the same consists in the novel combination and arrangement of parts to be hereinafter more fully described, illustrated in the accompanying drawings, and set forth in the appended claims.

In the drawing forming a part of this application and in which like-designating characters refer to corresponding parts throughout the several views, Figure 1 is a transverse sectional view partly broken away of the device in its opened extended position. Fig. 2 is a side elevation of a portion of the frame structure in its closed position. Fig. 3 is an enlarged detail sectional view through the sliding sleeve of the device. Fig. 4 is an enlarged perspective view of one of the rib hinges. Fig. 5 is a perspective view of the support or platform of the device, and Fig. 6 is an enlarged perspective view of one of the sliding collars of the foldable ribs.

Referring more in detail to the drawing the main shaft 10 of the parachute construction is provided at its lower end with a platform 11 adapted to support the person of the aeronaut, while securing or hand-hold straps 12, may also be employed if desired. A plurality of bow ribs 13 are hinged to a plate 14 mounted upon the top of the shaft 10, and over the said ribs the canopy or covering 15 is firmly secured.

A slidable sleeve 16 is mounted upon the shaft 10, the upward movement of which sleeve is limited by the stop 17 upon the shaft, while the same is retained in its lower position by means of a spring-pressed catch 18, which is provided upon the shaft to engage an opening 19 through the sleeve 16. Similarly, a spring-pressed catch 20 is adapted to retain the sleeve in its elevated position and with the device completely opened. Rigid ribs 21 are pivoted to the inner faces of the bow rib 13 and also to a collar 22 rigidly secured at the top of said slidable sleeve. Two sets of foldable ribs 23 which are provided with intermediate hinges 24 are pivoted between the inner sides of the bow rib 13 and their respective collars 25 which are slidably mounted upon the sleeve 16.

An expansion spring 26 is positioned between the top collar 27 of the sleeve 16 and the plate 14 at the end of the sleeve, and whereby, as will be evident, a normal downward closing tendency is imparted to the sleeve 16. With the parachute opened as illustrated in Fig. 1, the spring 26 is compressed between the plate 14 and collar 27 and the sleeve 16 is retained in this elevated position by its engagement with the upper latch 20, it being noted that all of the ribs are extended and the foldable ribs 23 are completely unfolded upon their hinges 24.

When desired to fold or collapse the parachute, the catch 20 is released and the spring 26 will forcibly lower the sleeve 16 drawing the ribs 21 downwardly, thus forcing the bow ribs 13 and the canopy 15 closed. In this operation, the ribs 23 assume their folded positions inwardly of the bow ribs, which action is permitted by the slidable mounting of the collars 25 upon the said sleeve, the elements assuming the folded position as shown in Fig. 2, and at which time the catch 18 comes into engagement with the sleeve.

A parachute designed to be formed of a considerable size is thus provided which will automatically open upon releasing the lower catch 18 and by means of the air pressure 105 entering beneath the canopy. The device is then automatically closed by the action of the spring 26 upon releasing the catch 20.

While I have shown and described the preferred embodiments of my invention, minor changes may be made in the form, proportion and details of construction there-

of, without departing from the spirit and scope of the invention as set forth in the claims.

What I claim is:—

- 5 1. A parachute, comprising a shaft, having a terminal plate upon one end thereof, a passenger supporting means at the other end of said shaft, a sleeve slidable upon said shaft, an expansion spring between said 10 plate and the adjacent end of said sleeve, radial bow ribs hinged to said plate, a canopy covering for said bow ribs, a collar rigidly secured to the top of said sleeve, and slidable similar collars mounted in spaced 15 relations to said secured collar and upon said sleeve, rigid ribs pivoted between said bow ribs and said secured collar, hinged ribs between said bow ribs and said slidable collars, and means for retaining said sleeve 20 in its upper and its lower positions with the

parachute in its respective open and closed relations.

2. A device of the class described, comprising a shaft, a sleeve slidably-mounted thereon, bow ribs hingedly connected to one 25 end of said shaft, an expansion spring between said ribs and the adjacent end of said sleeve, rigid ribs between said bow ribs and said sleeve and hinged ribs having their outer ends pivoted to the bow rib and slidable collars upon said sleeve having hinged 30 connections with the other ends of said hinged rib.

In testimony whereof I affix my signature in presence of two witnesses.

JAKOB SPYCHALSKI.
